CLAIM

We claim, the ornamental design for a boat with cover and strap assembly, as shown and described.

DESCRIPTION

FIG. 1 is a perspective view of a boat with cover and strap assembly, showing a first embodiment of our new design; FIG. 2 is a front view of the embodiment shown in FIG. 1; FIG. 3 is a back view of the embodiment shown in FIG. 1; FIG. 4 is a side view of the embodiment shown in FIG. 1; FIG. 5 is another side view of the embodiment shown in FIG. 1;

FIG. 6 is a top plan view of the embodiment shown in FIG. 1;

FIG. 7 is an enlarged partial view of FIG. 3;

FIG. 8 is a side view of the enlarged partial view shown in FIG. 7, with portions of the boat and cover removed for clarity;

FIG. 9 is a partial cross-sectional view of FIG. 4 taken along line 9-9-;

FIG. 10 is an enlarged partial view of FIG. 7;

FIG. 11 is an enlarged partial view of FIG. 7;

FIG. 12 is an enlarged partial view of FIG. 7;

FIG. 13 is a perspective view of a boat cover strap assembly, showing a second embodiment of our new design;

FIG. 14 is a front view of the embodiment shown in FIG. 13;

FIG. 15 is a back view of the embodiment shown in FIG. 13;

FIG. 16 is a side view of the embodiment shown in FIG. 13; FIG. 17 is another side view of the embodiment shown in FIG. 13;

FIG. 18 is a top plan view of the embodiment shown in FIG. 13;

FIG. 19 is an enlarged partial view of FIG. 15;

FIG. 20 is a side view of the enlarged partial view shown in FIG. 19, with portions of the boat and cover removed for clarity;

FIG. 21 is a cross-sectional view of FIG. 16 taken along line 21-21;

FIG. 22 is an enlarged partial view of FIG. 19;

FIG. 23 is an enlarged partial view of FIG. 19; and,

FIG. 24 is an enlarged partial view of FIG. 19.

The broken lines are for the purpose of illustrating portions of the article that form no part of the claimed design.

The dash-dot lines represent the boundaries of the enlarged partial view of FIGS. 9-12 and FIGS. 21-24 and form no part of the claimed design.
